RECTAL ANÆSTHETICS AND ANALGESICS

Ferdinand W. Nitardy, Brooklyn, N. Y., assignor
to E. R. Squibb & Sons, New York, N. Y., a
corporation of New York

No Drawing. Application March 31, 1933
Serial No. 663,852

4 Claims. (Cl. 167—52)

This invention relates to rectal anæsthetics and analgesics having an ether-oil base.

As hitherto constituted, combinations of ether with oils—though valuable for inducing anæsthesia or analgesia by rectal instillation, in connection with various operations, particularly the management of pregnancy and labor—have been defective in that their presence in the colon has caused irritation and discomfort to the patient, in some cases to such a degree as to result in expulsion of the mixture by reflex action; in consequence of which failure to retain, there has been serious interference with the induction of adequate anæsthesia or analgesia.

It is the object of this invention to provide ether-oil rectal anæsthetics and analgesics that give rise to the minimum of colonic irritation and discomfort, and are therefore completely retained and thus capable of exercising their full anæsthetic and analgesic effect.

In the practice of this invention, ether-oil combinations are mixed with a small proportion of an interface-tension depressant. By this addition, the discomfort the patient would otherwise experience is largely prevented, and hence the efficiency with which anaesthesia or analgesia may be induced is markedly increased.

Among the interface-tension depressants that may be used are sulfonated olein, and alkali-metal and ammonium salts thereof; sulfonated oleic acid, and alkali-metal and ammonium derivatives thereof; mono-esters of triethanolamine; and sulfonated castor, corn, cottonseed, olive, almond, peanut, peach-kernel, and neat's-foot oils. The oil in the ether-oil base may be any oleaginous material, especially mineral, vegetable, and animal oils, fats, and greases—e. g., liquid petrolatum, olive oil, lanolin—and is preferably used in the proportion of between one-half and three times the volume of ether.

As an example, a rectal anæsthetic constituted in accordance with this invention may comprise

Ether	2 fl. oz.
Liquid petrolatum	1 fl. oz.
Sulfonated olein	0.1% by weight
or	
Ether	2 fl. oz.
Olive oil	2 fl. oz.
Sulfonated olive oil	0.2% by weight

As a further example, a rectal analgesic constituted in accordance with this invention and especially suitable for obstetrical purposes may have the formula

Ether	2 1/2 fl. oz.
Quinine	20 gn.
Alcohol	45 min.
Liquid petrolatum enough to make	4 fl. oz.
Sulfonated olein	0.1% by weight

It will be understood that the foregoing examples are merely illustrative and by no means limitative of the invention, which may be variously otherwise embodied—for instance, as to the specific interface-tension depressants and oils and other ingredients employed, and as to their relative proportions—within the scope of the appended claims.

I claim:

1. A rectal anæsthetic or analgesic comprising ether, an oil, and an interface-tension depressant.

2. A rectal anæsthetic or analgesic comprising (1) ether, (2) an oil, and (3) a substance selected from the group consisting of sulfonated olein and alkali-metal and ammonium salts thereof, sulfonated oleic acid and alkali-metal and ammonium derivatives thereof, mono-esters of triethanolamine, and sulfonated castor, corn, cottonseed, olive, almond, peanut, peach-kernel, and neat's-foot oils.

3. A rectal anæsthetic or analgesic comprising ether, an oil, and sulfonated olein.

4. A rectal anæsthetic or analgesic comprising ether, an oil, and sulfonated olive oil.

FERDINAND W. NITARDY.
